UNITED STATES PATENT OFFICE.

HERMANN WIEDLING, OF NEW YORK, N. Y., ASSIGNOR TO THE WIEDLING MOTOR COMPANY, OF SAME PLACE.

AUTOMATIC CAR-BRAKE.

SPECIFICATION forming part of Letters Patent No. 378,992, dated March 6, 1888.

Application filed November 23, 1886. Serial No. 219,634. (No model.)

To all whom it may concern:

Be it known that I, HERMANN WIEDLING, of Sondershausen, Germany, residing in New York, N. Y., have invented certain new and useful Improvements in Automatic Car-Brakes, of which the following is a specification.

This invention has reference to those mechanisms which use the momentum or the tendency of cars or railroad-trains to move to bring 10 the same to a stop or to reduce and control the speed of the same.

The particular aims of the invention are to give to the brake an instantaneous action and to avoid the necessity of powerful mechanism 15 or apparatus to actuate or operate the same.

In carrying my invention into practice I use the rotation of the wheels or axles of the cars to revolve by friction wheel cylinders or shafts which wind up a chain or wire rope, 20 thereby operating the brake.

In the drawings I have shown my invention only applied to a car; but it is self-evident that the same construction of brake may be applied also for vehicles and all kinds of machinery where same could be of use—for example, for hoisting-machines, elevators, and different appliances for locomotion.

Referring to the accompanying drawings, Figure I is a side elevation of a railway-car with 30 the central portion in section. Fig. II shows a cross-section of Fig. I, taken on the dotted lines *y y*, looking in the direction of the arrow *a*. Fig. III is a similar cross-section, but seen in the direction of the arrow *b*. Fig. IV is the 35 front axle of the car, with car-wheels, friction-wheels, and drum for chain or wire rope, in section. Fig. V is an elevation of Fig. IV. Fig. VI shows the friction-wheel, which is keyed to the front axle; and Figs. VII and 40 VIII are elevations of opposite sides of the chain-drum or wire-rope drum with friction-faces. Fig. IX is a section taken on the line X X of Fig. V, showing the oscillating key which operates the friction-wheels; and Fig. 45 X is an elevation of Fig. IX with the key in section. Fig. XI is a section through the pedal of the front platform, by which, through the foot of the man in charge, the friction-

clutch, is operated, and it is shown in the position where the brake is not in operation. 50 Fig. XII represents a front view of same. Fig. XIII shows the top view of the frame for the pedal with the connecting-rod by which the key-shaft is moved. Fig. XIV represents a bottom view of the pedal. Fig. XV is a bottom view of the pedal mechanism with the crank to work the key-shaft, and Fig. XVI shows the pedal mechanism in the position where the friction-clutch is closed and the 55 brake will operate when the car-wheels revolve.

Referring to the drawings, 1 is the front and 2 the rear axle of the car. The brake-shoes 3 of the front wheels and the brake-shoes 4 of the rear wheels are carried and kept off 60 the wheels by springs 5. The vertical bar 6 forms a bearing for the pin 7 of lever 8. The latter works, through pins 9 and 10, the rods 11 and 12, which operate the brake-shoes 3 and 4. The other side of the car has a mechanism 65 similar to that described here. The lever 13, rods 14 and 15, pin 16, and vertical bar 17 correspond with lever 8, rods 11 and 12, pin 9, and vertical bar 6. The levers 8 and 13 are 70 bent and made in one piece with cross-bar 18, 75 which has in its middle an eye, 19, for the chain or wire rope 20.

Figs. IV and V show the front axle on a larger scale. To the same is keyed the friction-wheel 21, which has the circular face 22. 80 The cylinder 23, which is loose upon the front axle, 1, has an eye, 24, for the chain or wire rope 20, and its two arms 25 and 26 have friction-faces 27 and 28, which correspond to the annular face 22 of wheel 21. The collar 29 of 85 cylinder 23 bears on collar 30 of cylinder 31, which, as well as cylinder 32, is loose on axle 1. The cylinder 32 rests with collar 33 against the hub 34 of car-wheel 35, and projects with its square head 36 over the square head 37 of cylinder 31. Heads 36 and 37 have openings 38, 39, 40, and 41, in which fit the pins 42, 43, 44, and 45 of U-shaped key 46. The latter has in the axis of pins 42 and 43 the shaft 47, which has a bearing on the hanger 48 of the front 90 platform, 49, of the car. The spring 50, Fig.

IV, acts against the cylinder 23, and keeps thereby the friction-faces 22 and 27 separated.

On the front platform, 49, is put, in a convenient place for the man in charge, the pedal 51, which has the eyes 52, 53, and 54. Said pedal swings on bolt 55 of frame 56, and keeps, through eye 53 and bolt 57, the connecting-bar 58, which works by its eye 59 and the pin 60 the crank 61, which is fastened by pin 62 to shaft 47. The eye 54 of the pedal has on its bolt 63 the rack 64, which engages with its teeth 65 the stop 66 of frame 56 as it is driven by its weight. The rack 64 forms on top the extension 67, which can be conveniently worked by the toes of the foot to release the pedal from its position.

Having thus shown the combination of the parts of the mechanism, I will describe the way in which it is operated and in which it acts.

If the pedal 51 is in the position of Fig. XI, the key 46 will be, through pin 57, connecting-rod 58, eye 59, pin 60, crank 61, and shaft 47, kept in the position shown in Fig. IV, and thereby the cylinders 28 and 31 be forced by the spring 50 toward the cylinder 32, and so the friction-faces 27 and 28 of cylinder 23 are kept away from the face 22 of the friction-wheel 21. As now the springs 5, which carry the brake-shoes 3 and 4, face the latter from the car-wheels, a tension is produced in the chain or wire rope 20, as rods 11 and 12 and lever 8 are forced in directions indicated by the arrows of Fig. I, and as rope 20 thereby draws on eye 24 of cylinder 23, the latter cannot revolve, and so the brake-shoes are kept away from the car-wheels and the brake will not be in operation. If the man in charge disengages the rack 64 by working the extension 67 with his toes and brings the pedal 51 in a position shown in Fig. XVI, by depressing the same with his heel the connecting-rod 58 depresses thereby the crank 61, and so shaft 47 makes a part of a revolution as it turns in hanger 48 and on the pins 42 and 43 of its key 46. The pins 42 and 43 have a stationary bearing in the slots 38 and 39 in head 36 of cylinder 32, and the latter is kept from revolving with the axle 1 by the pins 42 and 43, and it also has no movement sidewise, as it rests against the hub 34 of the car-wheel 35. The shaft 47 is in a line with pins 42 and 43, as their bearings are stationary. The pins 44 and 45 are moved through the movement of shaft 47 and U-shaped key 46 on pins 42 and 43 as centers. Thereby pins 44 and 45 will force head 37, with its cylinder 31 and flange 30, against flange 29 of cylinder 23, and so the arms 25 and 26 of the latter are pressed with their friction-faces 27 and 28 against annular face 22 of friction-wheel 21. If the car is now running, the friction-wheel 21 revolves with axle 1, as it is keyed thereon, and the friction created by the pressure between annular face 22 and corresponding faces 27 and 28 will, through arms 25 and 26, cause the cylinder 23 to re-

volve with the axle 1, and so the rope or chain 20 be wound up on the cylinder 23, whereby the levers 8 and 13 are moved through eye 19 and cross-bar 18, and as the combined levers 8 and 13 swing on their pins 7 and 16, the rods 11, 12, 14, and 15 force the brake-shoes 3 3' and 4 4' against the tension of springs 5 against the car-wheels, thereby controlling or reducing the speed of the car. The friction created between the annular face 22 and faces 27 and 28 is in proportion to the pressure applied at the pedal 51 of the front platform, and, again, the force with which the rope 20 will work the brake-shoes 3 3' and 4 4', through the levers 8 and 13 and the rods 11, 12, 14, and 15, against the car-wheels is in proportion to the friction produced between the faces 22 and 27 28, and thereby, also, the friction produced on the car-wheels through the brake-shoes is always in proportion to the pressure applied on the pedal 51. Thus the brake can be applied with more or less force by using more or less force on the pedal 51.

By allowing the rack 64 to engage with stop 66 the brake can be retained in any position without further attention being required.

If the pedal 51 is again brought into the position shown in Fig. XI, the spring 50 will separate the device 25 from friction-wheel 21, and the tension produced in rope 20, through springs 5 and the weight of levers 8 13 and cross-bar 18, will unroll said rope 20 from the cylinder 23 by rotating the cylinder in the opposite direction to that in which it wound up the rope.

The rope 20 will be wound up always in the direction the wheels of the car revolve, and therefore when the car runs backward the direction in which it will be wound and unwound will be reversed.

When the brake is put in operation, the cylinder 23 will wind up the rope 20 until the tension of the latter overcomes the friction of the device 25 on the wheel 21 and keeps the cylinder 23 stationary, whereby the annular face of the wheel 21 slides on the faces 27 and 28 and the collar 29 on the collar 30 of the cylinder 31 as long as the wheels of the axle 1 revolve.

If the brake is not in operation, no rope is on the cylinder 23, as the rope is only long enough under these circumstances to connect directly the eye 24 of the cylinder 23 with the eye 19 of the cross-bar 18. Thereby only a small part of a revolution of the cylinder 23 is required to produce a tension on said rope 20 sufficient to overcome the springs 5 and bring the brake-shoes in contact with the car-wheels.

Having thus described my invention, what I claim as new and my invention, and desire to secure by Letters Patent of the United States, is—

1. The combination, with the platform of a car, of the stop 66, rack 64, pedal 51, and rod 130

58 to connect said pedal with the brake mechanism of a car, substantially as and for the purposes set forth.

2. The combination, with the brake mechanism of a car, of the shaft 47, provided with a U-shaped key 46, pins 42 43 44 45, cylinder 32, provided with openings 38 39 in its head, and cylinder 31, provided with openings 40

and 41 in its head, whereby the brake mechanism of the car can be set by rotating the shaft 47, substantially as and for the purposes set forth.

HERMANN WIEDLING.
